UNITED STATES PATENT OFFICE.

AUGUSTUS E. SCHLIEDER, OF BUFFALO, NEW YORK, ASSIGNOR TO MONARCH ACETYLENE GAS COMPANY, OF OMAHA, NEBRASKA, A CORPORATION OF NEBRASKA.

CARBID-FEED MECHANISM FOR ACETYLENE-GAS GENERATORS.

No. 873,176.

Specification of Letters Patent.

Patented Dec. 10, 1907.

Application filed May 25, 1906. Serial No. 318,668.

To all whom it may concern:

Be it known that I, AUGUSTUS E. SCHLIEDER, a citizen of the United States, residing at Buffalo, in the county of Erie and State 5 of New York, have invented certain new and useful Improvements in Carbid-Feed Mechanism for Acetylene - Gas Generators, of which the following is a specification.

This invention relates to carbid feed- 10 mechanism for acetylene generators, and its primary object is the production of feed- mechanism, in which a double closure is pro- vided between the carbid-receptacle and the gas-generating-chamber to prevent the over- 15 feeding of carbid if for any reason any of the feeding-mechanism should refuse to operate.

Other objects are, the provision of pos- 20 sitive and simple controlling - mechanism whereby either of the closures is held closed. 25 while the other is open; to provide a double hopper for the carbid-receptacle to so ar- range the closures with respect to each other that a measured quantity of carbid is fed into the gas generating-chamber at each charge; 30 and to otherwise improve on feeding-mech- 35 anism for this purpose now in use.

To these ends the invention consists in the construction, arrangement, and combination of parts to be hereinafter described and 40 pointed out in the appended claims.

In the drawings, —Figure 1 is a side eleva- 45 tion of that portion of an acetylene gas-gen- erator containing the feed-mechanism. Fig. 2 is a central vertical section taken on line 2—2, Fig. 3, looking toward the left. Fig. 3 50 is a central vertical section taken on line 3—3, Fig. 1. Figs. 4 and 5 are side elevations of the controlling - mechanism, showing the same in different positions. Fig. 6 is a sec- 55 tion similar to Fig. 2, showing the valves in a different position. Fig. 7 is a plan view of the parts shown in Fig. 1. Fig. 8 is a de- 60 tached perspective view of the retaining lever of the controlling-mechanism. Fig. 9 65 is a perspective view of the curved trip-cam. Fig. 10 is a vertical section taken on line 70 10—10, Fig. 3, looking in the direction of the arrow crossing said line. Fig. 11 is a section taken on line 11—11, Fig. 7.

55 Referring to the drawings in detail, like letters of reference refer to like parts in the several figures.

The reference letter A designates the valve- 59 chamber which may be of any form or size,

and which is located between the carbid-re- 55 ceptacle B and the gas generating-chamber C of the generator. The valve-chamber is se- cured to generating-chamber C by means of a casting D, and the carbid-receptacle is se- 60 cured to the upper end of the valve-chamber by means of a casting E.

Within the carbid-receptacle at the lower 65 end thereof is a breaker-wall in the form of a hopper or conical tube F having its lower or small end separated from the surrounding wall by an annular space G, and projecting downward into the valve-chamber C is a hopper or conical tube H which is located below the hopper or tube F and whose upper or large end is of greater diameter than the 70 lower or small end of tube F. In this man- 75 nner a double hopper-bottom is provided, the upper of which serves as a breaker-wall to loosen or agitate the carbid as it passes through the restricted end thereof and thus prevent packing of the carbid in the lower hopper. The lower edge of tube H is curved, as shown at h, and at one side has a notch h'.

Extending horizontally through the valve- 80 chamber in line with the vertical center of the hopper H, is a shaft I which is journaled in bearings i and has a segmental bucket-valve J secured thereto which is adapted to be swung underneath the said hopper to close the same. Within the valve-chamber beneath 85 said segment-valve is a third hopper or con- 90 ical tube K having its upper or large end se- cured to the walls of the valve-chamber and forming a chamber beneath the carbid-re- ceptacle. Normally closing said tube is a 95 gate or valve L secured to a horizontal shaft M journaled in suitable bearings m in the walls of the valve-chamber. This valve is some- 100 what shorter than the opening at the bottom of the tube K which it is designed to close against the flow of carbid, so that it may act to shear any particles of carbid that may lodge between the end thereof and the edge of said tube, and thus permit of its being moved to its closed position where it effectu- 105 ally prevents the feeding of carbid into the gas-generating-chamber until a new charge is needed. The space between the end of said valve and the tube K is of a size to pre- vent small particles of carbid passing there- through; but in cases where granular carbid is used, there need be only sufficient clearance between the tube and the valve to allow the

latter to enter the tube; or in such cases, the valve may close against the edge of the tube, if desired.

Shafts I and M extend out through the 5 valve-chamber through stuffing-boxes n; shaft I having secured to its outer end a lever O actuated by a slotted rod o secured to a gas-bell, as is common, and rising and lowering therewith; thereby rocking shaft I 10 and causing segment-valve J to open and close the lower end of hopper H, which serves as a continuation of the side walls of the carbid-receptacle.

Secured to shaft I is a depending retainer- 15 lever P having a laterally extended lower end with the underside thereof curved. An offset arm p extends from the forward end of said laterally extending-portion, and projecting from the inner side of said arm at or 20 near the end thereof is a pin p¹. A depending-lug p² is cast integrally with said arm and is adapted to strike shaft M to limit the rearward movement of said retainer-arm. Pivotally secured to the outer side of the retainer-arm is a detent-pawl R having an 25 outwardly extending longitudinal ledge r and an inwardly projecting stop-pin r¹ which bears against one of the lateral extensions of the retainer-lever, as at r², to limit the downward movement of said pawl.

S designates a cam-lever secured to shaft M directly beneath retainer-lever P and having its upper edge concaved to correspond to the lower curved edge of said retainer-lever. 35 At its forward end cam S has an outwardly and upwardly extending bracket s from which projects an inwardly directed pin s¹. A pin or stud s² extends inwardly from the opposite end of said cam and between said 40 pin or stud and pin p¹ on the retainer-lever, a retractile spring T is positioned, said spring being preferably used in conjunction with a short chain t to permit the spring to hang loosely when not under tension; one end of 45 said spring being secured to pin s² and its other end connected to said chain which is also connected to pin p¹ on the retainer-lever. The curved lower extended end of the retainer-lever bears against the concaved 50 edge of the cam S and prevents rocking of the latter until the rear end of said lever is moved forward of the axis of the cam, when, through the action of spring T said cam is induced to rotate; but this is impossible owing 55 to the detent-pawl engaging pin s¹. The ledge r of said pawl is of sufficient length to prevent rotation of the cam until the segment-valve is closed, after which the detent-pawl clears pin s¹ and permits the cam to 60 rock, thereby opening the valve L.

The operation of the device is as follows.— When first placing the device in use, the parts are in the position shown in Figs. 1 to 3, in which position the retainer-lever is in 65 engagement with the cam S, and the upper

or segment-valve is open while the lower valve is closed. The carbid-receptacle is supplied with carbid, a portion of which enters the chamber between the hopper H and valve L. Shaft I is now rocked by hand, 70 which causes the parts to assume the position shown in Figs. 5 and 6, in which position the upper valve is closed and the lower valve is open, and the retainer-lever P disengaged from the cam S. This operation causes the 75 carbid between hopper H and valve L to be deposited into the gas generating-chamber to evolve gas which is directed by a suitable pipe to a gasometer of common construction of which slotted rod o forms a part. The 80 gas entering the gas-bell causes the same and attached rod o to rise, thereby compelling shaft I to rock and move the several parts from the position shown in Figs. 5 and 6, to the position shown in Figs. 1 to 3. On consumption of the gas, the gas-bell lowers, and attached rod o causing a gradual movement of the retainer-lever P along the concaved upper edge of cam S, during which movement spring T is placed under tension and 85 exerts its power in the effort to rock the cam and shaft M to which valve L is secured, but before the rear end of the extended lower portion of the retainer-lever passes over the axis of said cam, detent-pawl R rides underneath pin p¹ on the cam and retains the latter in its normal position. Meanwhile, spring T is placed under greater tension and when the ledge of said pawl has passed said pin, the cam is rocked quickly, thereby causing valve L to open quickly and supply a full charge of carbid. Spring T is relaxed in 90 both extreme positions of the various parts, and is placed under tension only during the latter portion of the forward movement of 95 the retainer-lever. During the rearward movement of the parts, the rear extended end of the retainer-lever first strikes the cam at a point in rear of its axis, causing the same to rock in reverse direction, and as the co-acting corresponding edges of the retainer-lever and cam are brought together, pin p¹ strikes the underside of the ledge on the detent-pawl and causes said pawl to rise until the front edge of the same passes over said 100 pin, whereupon it gravitates and stop-pin r¹ strikes the upper side of the extended portion of the retainer-lever and limits its further movement.

This invention is susceptible to many 105 changes in the construction, formation and disposition of parts without departing from the spirit thereof or sacrificing any of the advantages.

Having thus described my invention, what 110 I claim is,—

1. In an acetylene gas-generator, the combination with a carbid-receptacle, a gas generating-chamber, and a valve-chamber between the two, of two shafts journaled in the 115

wall of said valve-chamber, a valve on one of said shafts adapted to close the carbid-receptacle, a valve on the other shaft adapted to close the outlet of the valve-chamber, a 5 segment cam on one of said shafts, means on the other shaft co-acting with said segment-cam, a spring between said cam and its co-acting means and normally inactive, said segment cam being held against movement 10 until the means co-acting therewith has been moved a predetermined distance and said spring being placed under tension during the movement of said co-acting means to cause said cam to move when said co-acting means 15 reaches a predetermined point.

2. In an acetylene gas-generator, the combination with a carbid-receptacle, a generating-chamber, and a valve-chamber between the two, of a valve adapted to close said carbid-receptacle, a valve adapted to close said valve-chamber, shafts extending out through the valve-chamber to which said valves are secured, means to prevent movement of the second mentioned valve until after the first- 25 mentioned valve has traveled a predetermined distance, and a spring to cause the said second-mentioned valve to open after the said first-mentioned valve has traveled its predetermined distance.

3. In an acetylene gas-generator, the combination with a carbid-receptacle, a gas-generating chamber, and a valve-chamber between the two, of two shafts journaled in the wall of the valve-chamber, a valve on one of 35 said shafts adapted to close the carbid-receptacle, a valve on the other shaft adapted to close the outlet of the valve-chamber, a segment-cam on the last-mentioned shaft, and means on the other shaft co-acting with 40 said segment-cam and adapted to prevent movement of said cam in one direction until said other shaft has been rotated a predetermined distance also to cause movement of said cam in the opposite direction.

4. In an acetylene gas-generator, the combination with a carbid-receptacle and a chamber beneath said receptacle, of a shaft extending out through the wall of the generator, a valve on said shaft adapted to close 50 said receptacle, a second shaft also extending out through the wall of the generator, and a valve secured to said second shaft and adapted to close the chamber beneath the carbid-receptacle, a segment-cam on the last-mentioned shaft, a retainer-lever on the first- 55 mentioned shaft co-acting with said segment-cam, a spring connecting said lever and said cam to cause the latter to rotate after the lever has traveled a predetermined distance, 60 and means for rotating the first mentioned shaft.

5. In an acetylene gas-generator, the combination with a carbid-receptacle and a chamber beneath said receptacle, of a shaft 65 extending out through the wall of the gen-

erator, a valve on said shaft adapted to close said receptacle, a second shaft also extending out through the wall of the generator, and a valve secured to said second shaft and adapted to close the chamber beneath the carbid- 70 receptacle, a segment-cam on the last-mentioned shaft having a concaved upper edge, a retainer-lever having a convex lower edge bearing against the said concaved edge of the cam, and means for causing said cam to rotate after the retainer-lever has traveled a predetermined distance. 75

6. In an acetylene gas-generator, the combination with a carbid-receptacle and a chamber beneath said receptacle, of a shaft 80 extending out through the wall of the generator, a valve on said shaft adapted to close said receptacle, a second shaft also extending out through the wall of the generator, and a valve secured to said second shaft and adapted to close the chamber beneath the carbid-receptacle, a cam having a concaved upper edge and a pin extending inward, a retainer-lever having lateral extensions at its lower 85 end providing a curved edge to co-act with the concaved edge of the cam and having a pivoted detent-pawl adapted to ride underneath the pin of the cam, and a spring serving to rotate said cam when said detent-pawl has passed underneath the pin on the 90 cam.

7. In an acetylene gas-generator, the combination with a carbid-receptacle and a chamber beneath said receptacle, of a shaft 100 extending out through the wall of the generator, a valve on said shaft adapted to close said receptacle, a second shaft also extending out through the wall of the generator, and a valve secured to said second shaft and adapted to close the chamber beneath the carbid-receptacle, a cam having a concaved upper edge and an offset portion at one end provided with an inwardly directed pin, a retainer-lever having opposite lateral extensions at its lower end provided with a convex lower edge co-acting with the concave-edge of said cam, said lever having also a 105 detent-pawl with an outwardly extending curved ledge which rides underneath the pin on said cam and a depending stop adapted to 110 strike said second mentioned shaft to limit the rearward movement of said lever, said detent-pawl serving to prevent rotation of the cam until said detent-lever reaches a certain point in its forward movement, and a 120 spring connection connecting one end of said cam with the opposite lateral extension of the retainer-lever.

In testimony whereof, I have affixed my signature in the presence of two subscribing 125 witnesses.

AUGUSTUS E. SCHLIEDER.
